UNITED STATES PATENT OFFICE.

MICHAEL C. BROWNE, OF HOLYOKE, MASSACHUSETTS.

STRIP-MOISTENING DEVICE.

No. 868,840.

Specification of Letters Patent.

Patented Oct. 22, 1907.

Application filed June 3, 1907. Serial No. 376,970.

To all whom it may concern:

Be it known that I, MICHAEL C. BROWNE, a citizen of the United States of America, residing at Holyoke, in the county of Hampden and State of Massachusetts, 5 have invented new and useful Improvements in Strip-Moistening Devices, of which the following is a specification.

This invention relates to improvements in moistening devices for gummed pasting strips, labels, or other 10 similar gummed articles, and is particularly adapted for moistening a continuous paper strip or other material that has previously been coated on both sides with a suitable solvent adhesive material, the strip being simultaneously moistened on both sides when withdrawn 15 from said device.

Broadly considered, the invention consists in providing a continuous roll of paper or other material coated on both sides with a soluble adhesive material, and means for moistening simultaneously both sides 20 of the strip when drawn from the roll, the strip being torn off or severed when a suitable length has been withdrawn from the roll. The moistened strip is designed to be used in securing the ends of wrapping paper that have been previously wrapped about a 25 package.

Heretofore, it has been the customary practice to secure the ends of wrapping paper by means of a suitable sealing wax or cord, and my improvement is primarily designed to moisten a strip of gummed paper that 30 is to be used as a substitute for sealing wax, or a cord.

The details of my invention will be fully described in the specification with reference to the annexed drawings.

In the drawings forming part of my application,— 35 Figure 1 is a plan view of my improvement showing the separate receptacles for containing the moistening fluid and with one of the covers removed, and the gummed strip passing over one of the moistening wicks and under the other. Fig. 2 is a longitudinal section 40 on the line 2—2, Fig. 1, through one of the wick-supporting rolls, showing the separate receptacles for the moistening fluid and the ends of the moistening wicks immersed in the same, also the covers in sectional elevation. Fig. 3 is a transverse section on the line 3—3, 45 of Fig. 1, showing the cylindrical rolls for supporting the moistening wick and also the bracket or fork for supporting the continuous strip of gummed paper. Fig. 4 is a partial sectional view of the overlapping ends of the wrapping paper and showing the gummed 50 strip intermediate the ends prior to being pasted to the edge of the wrapping paper. Fig. 5 is a detail, perspective view, showing how the strip is to be used in wrapping a package.

Referring to the drawings in detail, *a* designates a 55 suitable base-piece and at the opposite ends of this base-piece the receptacles *b* are provided (by means

of the walls *c* and *d*) for containing the moistening fluid, designated by *e*. The walls *c* are made much higher than the walls *d*, as shown clearly in Fig. 2, so that the moistening rolls *f* can be suitably supported 60 in openings therein.

Covering the outer cylindrical surface of the rolls *f* is a tubular shaped absorbent material, preferably hump-wicking, the ends of which, after leaving the rolls *f*, are immersed in the moistening fluid *e* as clearly 65 shown in Fig. 2.

It is apparent from this construction, that the portion of the fabric *h* which surrounds the rollers *f* will be thoroughly and quickly moistened by reason of the rapid capillary attraction of the loose ends of the fabric. 70

Referring to Fig. 3, it will be seen that there are provided two rollers *f* and moistening fabrics *h*, *h*, so that a strip of gummed paper *i*, when drawn from a suitable roller *j*, will be simultaneously moistened on both sides during the operation of drawing the gummed 75 strip across the moistening wicks. The roller *j*, which contains the continuous strip of gummed paper, is mounted in the bracket *k* which carries the shaft *m* and is free to rotate in the bracket *k*.

n indicates a slotted fork or arm that is rigidly secured to the shaft *m* and is held in different positions of adjustment by means of the thumb-nuts *n*¹. 80

A roller *o* that bears against the underside of the roll of gummed paper *a*¹ is loosely mounted on the shaft *m*.

The roll *j* is carried by the shaft *p* which works freely 85 in a vertical slot *q* of the slotted forks *n*, and as the paper is withdrawn from the roll, the shaft *p* falls and always allows the outer surface of the same to bear on the roller *o* and rotate the same. By means of this construction, the forks *n* may be adjusted by means of 90 the thumb-nuts *n*¹ with relation to the rolls *f* whereby the strip *i* will always engage the rolls *f* at any desired angle, according to the conditions of the gummed strip, that is whether the coating is a heavy or a thin 95

The space *c*¹ between the uprights *c* permits the dripping from the moistening wicks *h* that contain more or less of the gum to fall therein without coming in contact with the clear moistening fluid *e*, and if necessary, a tray can be inserted in this space between 100 the uprights *c*.

After the moistening wicks *h* become filled with the gum so that the capillary attraction is greatly lessened, the rolls *f* can be rotated by hand and a new surface of the wick brought in contact with the moistening strip; 105 but in the normal operation of drawing the gummed strip *i* over the surfaces of the moistening wick, the rollers *j* do not rotate. The rollers *f* and the wicks *h*, it will be observed by reference to Fig. 2, are mounted in openings *r* of the walls *c* so that the wicks and rolls *f* can be rotated as a whole by the hand. 110

In using the moistening device, the gummed strip

i is drawn from the roller *j* until a suitable length is moistened, when it is torn off and placed near the edge of the wrapping paper, indicated at *s* in Figs. 4 and 5, and the other end *t* of the wrapping paper, after being drawn tightly around the package, is firmly pressed onto the other side of the moistened strip *i*, whereby the wrapping paper is securely held in place. Fig. 5 clearly indicates how this strip is used in securing the free ends of the wrapping paper.

10 Suitable covers *u* for protecting the moistening fluid and ends of the wicks are provided, as clearly shown in Fig. 2.

A suitable severing element *v* having a serrated edge is employed for detaching a strip after the same is withdrawn from the apparatus. Also a nut *w* may be employed to clamp the rollers *f* in a fixed position. The strip from the roller *j* may be drawn from the lower side, if desirable.

What I claim, is:—

20 1. A gummed strip moistening device having in combination a base-piece, liquid containing receptacles mounted thereon, rollers, absorbent material incasing the rollers and having pendent ends submerged in the liquid contained in said receptacle, whereby when a strip is passed under one roller and over the other it will be moistened on its opposite faces.

2. In a strip moistening device, in combination, a base-piece, liquid-containing receptacles spaced from each other, rollers spanning the space, moisture absorbent materials 30 carried by the rollers and having a portion thereof immersed in the liquid whereby a strip may be simultaneously moistened on its opposite sides.

3. A strip-moistening device having in combination a pair of rollers, a moisture absorbent material incasing the 35 same and having pendent ends entering the moistening fluid, means for rotatably supporting the rollers, the roll-

ers being arranged in parallelism, means for adjustably supporting a coiled strip of material gummed on both sides, the strip being passed under one roller and over the other roller and in contact with the absorbent material, 40 whereby both sides of the strip are simultaneously moistened, as described.

4. A gummed strip moistening device having in combination a base-piece, liquid receptacles located at opposite ends of the same, one of the sides of the receptacles having openings at their upper ends, rollers mounted in the openings, absorbent material incasing the rollers and having pendent ends entering the liquid, means for rotatably supporting a continuous strip, whereby when the strip is drawn through the device the same is moistened 45 on opposite faces, as described.

5. A gummed strip moistening device having in combination a base-piece, liquid receptacles located at opposite ends of the same, one of the sides of the receptacles having openings at their upper ends, rollers mounted in the 50 openings, absorbent material incasing the rollers and having pendent ends entering the liquid, means for rotatably supporting a continuous strip whereby when the strip is drawn through the device the same is moistened on opposite faces, and means for varying the angular position of 55 the strip with relation to one of the rollers, as described.

6. A gummed strip moistening device having in combination a base-piece, liquid receptacles located at opposite ends of the same, one of the sides of the receptacles having openings at their upper ends, rollers mounted in the 60 openings, absorbent material incasing the rollers and having pendent ends submerged in liquid, means for rotatably supporting a continuous strip whereby when the strip is drawn through the device, the same is moistened on opposite faces, and means for locking the rollers against rotation, as described.
